UNITED STATES PATENT OFFICE.

JOHN ASHMORE AND GEORGE ASHMORE, OF PHILADELPHIA, PENNSYLVANIA.

WARP-CUTTING DEVICE FOR USE IN PILE-FABRIC LOOMS.

Application filed April 20, 1923. Serial No. 633,377.

To all whom it may concern:

Be it known that we, JOHN ASHMORE and GEORGE ASHMORE, both citizens of the United States, residing in the city and county of Philadelphia and State of Pennsylvania, have jointly invented a new and useful Warp-Cutting Device for Use in Pile-Fabric Looms, of which the following is a specification.

- 10 Our invention relates to a class of devices employed to sever the warps of woven fabrics out of which velvet, Axminster or Wilton carpets, for instance, or other pile fabrics, are made, and which is variously termed, in
 15 the shop as a carpet wire, and, in untechnical language, as a cutting knife.

Confining ourselves to the expression cutting knife, it is to be explained that in pile-fabric looms a plurality of these cutting 20 knives, identical with each other, is used, and that their curved cutting edges are drawn through the warps by various devices, the knives, from a normal plural placement in the loom, being one by one drawn through 25 the fabric, and each, after it has done its work of cutting the warps, being returned to its original position.

As these knives have heretofore been formed, it has been necessary to constantly 30 sharpen their cutting edges, sometimes very frequently indeed, in order to prevent the tearing of the yarn resulting in practice from the operation of these knives when their blades are dull.

35 It is the object of our invention to lessen and almost wholly overcome the tendency of these blades quickly to become dull, and this object we attain by the simple expedient of cutting an oblique slot into the outwardly and upwardly extending curved cutting edge 40 of the blade of the cutting knife as an entirety,—the knife being otherwise similar in general characteristics and formation to those which for many years have been in use 45 in the art of making pile fabrics.

It should be further explained that our invention resides essentially in this construction of the cutting blade of the cutter, and that in order to effectuate the mounting and 50 reciprocatory movement of the cutters across the fabric and lengthwise of the loom, a loom the framework of which may be of any conventional or desired construction, and a means for reciprocating the cutters 55 one by one along said framework similarly

of any preferred construction operative to the end in view, are to be employed.

In order to illustrate a loom in which to mount and a means to reciprocate our cutters, we have in the accompanying drawings 60 represented typical embodiments, in Figure 1 in side elevation and in Figure 2 in fragmentary perspective, of so much of a loom as is adapted to carry and permit of the operation of, and a means for reciprocating, 65 our cutters,—illustrating in Figure 3 in perspective a cutter embodying our invention.

Similar numerals of reference indicate corresponding parts.

Referring to the drawings:

1 designates a loom framework of any preferred character, and 2 a cutter-carrying bed upon which are mounted our cutting knives 3, one of which detached is illustrated in Figure 3, and any desired plurality of 75 which as mounted is illustrated in Figure 2.

As a convenient means for effecting the reciprocation or end-for-end travel of a slide 4 along the slide-way 2, we use the following connective gearing:

6 designates a pair of fast and loose pulleys suitably mounted upon a driving shaft 7, a pinion 8 on the free-end of which shaft engages with a spur wheel 9 on a driven shaft 10 suitably mounted on the 85 framework and having at its free end a driving bevel gear 11 in engagement with a driven bevel gear 12, which being connected with a disc on which is an eccentric pin 13 serves as an eccentric—an eccentric rod 14 90 making connection with the lower end 15 of a bell-crank lever 16, the upper end of which is by a link 17 connected with the slide 4.

Obviously, when the driving shaft 7 is caused to rotate, through the pinion 8, the 95 spur wheel 9, the driven shaft 10, the driving bevel gear 11, the driven bevel gear and eccentric 12, the eccentric rod 14, the bell-crank lever 16, and the link 17, the slide 4 will be caused to reciprocate in its slide-way 100 on the cutter-carrying bed 2.

The connection between the slide and the cutting knives is through a hook 18 pivoted to the slide 4 and adapted to engage with the hook recesses 19 near the base 29 of the cutting knife 3, as particularly illustrated in Figure 3.

All of the foregoing operative devices being usual in looms of this character require no further description, but it may not 110

be improper to explain that after each cutting knife has in turn been drawn through the warps, it is moved laterally across the cutter-carrying bed 2, conveniently 5 by the properly timed operation of what we term a replacing hook 20, mounted on the free end of a transverse bar 21, which moves through a slide bearing 22 mounted on the framework and is caused so to move 10 through connection with the upper end of a rocker arm 23 pivoted at 24, the lower end of which arm travels upon a cam 25 mounted upon a cam shaft 26 housed in the framework and driven by a toothed pinion 27 in 15 engagement with the spur wheel 9,—and that thereafter said cutting knife will be returned to its normal position in the plurality of knives.

28 designates the usual take-up roll for 20 the fabric which is to be operated upon.

Repeating the statement that the above described loom framework and means for reciprocating the cutters, are typical merely of devices in general use for the purposes 25 mentioned, and that other means operating to support and actuate the cutters may in their stead be employed,—the cutting knife, or carpet wire as it is technically called and which is illustrated in Figure 3, is the device in which our invention primarily resides and is of the following construction:—

A long shank designated by the number 3 terminates at the rear in the base or butt-end formation designated 29, the peculiar 35 outlining of which is well understood by those skilled in the art and need not, therefore, be specifically described except to say that it necessarily embodies the hook recess 19 into which the hook 18 on the side 4 is 40 entered to effect the pull upon the cutter.

The advance end of the cutting knife is, however, formed into the usual outwardly and upwardly-extending curved cutting blade which we have designated 30, the sides 45 of which are oppositely curved inwardly to the cutting edge designated 31, so that viewed in transverse section the cutting

blade presents, in a sense, the curvature of an old fashioned razor blade.

32 designates a slot cut obliquely into the 50 cutting blade 30 within the confines of the cutting edge 31.

It is due to the introduction of this slot into the blade that we secure the result outlined in the preamble of this specification, 55 of great durability of the cutting edge, a result in which the advantage of our invention inheres.

We do not confine ourselves to the depth or specific degree of inclination of the slot with 60 reference to the longitudinal axis of the blade as an entirety, or to the relative inclination of said slot with reference to the curved cutting edge 31 of the blade.

We have, however, illustrated in Figure 65 3 of the drawings a good depth and inclination which in practice is at present preferred by us because we have found it to give satisfactory and reliable results.

Having thus described our invention, what 70 we claim as new and desire to secure by Letters Patent, is:—

1. A pile-wire having a blade, the cutting edge of which extends in a rearwardly direction, said blade having a slotted portion 75 the slot of which extends in substantially rearwardly direction and intersects said cutting edge.

2. A pile-wire having formed integral therewith a blade, the cutting edge of which extends in a rearwardly direction, said blade having a slotted portion the slot of which extends in a substantially rearward direction and intersects said cutting edge to provide a relatively flexible cutting portion. 85

In testimony whereof we have hereunto signed our names this 19th day of April, A. D. 1923.

JOHN ASHMORE.
GEORGE ASHMORE.

In the presence of—

N. BUSSINGER,
EMILY IZORA VOGDES.
